CLAIM

The ornamental design for base for a cordless telephone, as shown and described.

DESCRIPTION

FIG. 1 is a top orthographic view of one embodiment of a base for a cordless telephone showing our new design; FIG. 2 is a bottom orthographic view thereof; FIG. 3 is a front orthographic view thereof; FIG. 4 is a rear orthographic view thereof; FIG. 5 is a right side orthographic view thereof; and, FIG. 6 is a perspective view thereof.

The broken lines shown in FIGS. 1-6 are included for the purpose of illustrating environmental elements only and form no part of the claimed design.
